UNITED STATES PATENT OFFICE

2,501,460

EXTRACTOR

Thomas S. Watson, Milwaukee, Wis., assignor to
 Huebsch Manufacturing Company, Milwaukee,
 Wis., a corporation of Wisconsin

Application September 14, 1945, Serial No. 616,196

2 Claims. (Cl. 68—242)

1

The invention relates to compression extractors and more particularly to that type of extractor in which fluid pressure exerted against a flexible diaphragm compresses the material operated upon between said diaphragm and an apertured portion of an enclosing casing to extract liquid from said material.

In extractors of the type above described the flexible diaphragm is usually provided with a beaded edge which is clamped between the casing and a retainer ring, and in some instances this type of anchorage has given trouble because of the cracking or splitting of the diaphragm at the anchorage point. The object of the present invention is to provide a new and improved form of anchorage connection for the diaphragm with the casing which eliminates the possibility of the cracking or splitting of the diaphragm at or adjacent to the joint.

A further object of the invention is to provide an arrangement in which the diaphragm anchorage is not a load transmitter for the cover, but this load is taken independently of said anchorage connection through a separate connection between the cover and the frame of the machine.

The invention further consists in the several features hereinafter set forth and more particularly defined by claims at the conclusion hereof.

Referring to the drawings:

Fig. 1 is a vertical sectional view of an extractor embodying the invention;

Fig. 2 is a horizontal sectional view taken on the line 2—2 of Fig. 1;

Fig. 3 is a detailed vertical sectional view taken on the line 3—3 of Fig. 2;

Fig. 4 is a view similar to Fig. 1 showing a modified form of the invention;

Fig. 5 is a detailed vertical sectional view taken on the line 5—5 of Fig. 4.

Figs. 1 to 3 show the invention incorporated in an extractor of the type shown in my co-pending application Serial No. 558,255, filed October 11, 1944, embodying an apertured extension between the usual top of such extractors and the cover. The extractor comprises a metal walled container 6 having an annular flange 7 spaced from its upper rounded edge 8 and an opening 9 in its bottom connected by a pipe 10 to a valve 11, which controls the inlet of pressure fluid from a pipe 12 and the outlet of said fluid through a pipe 13, said valve being operated manually through a rotatable shaft 14 and a lever 15 connected thereto. The pipe 12 is connected to a suitable source of pressure fluid, such as water, steam, or compressed air.

The container 6 is mounted in a suitable frame 16, which is formed with a cylindrical wall extension 17 and an annular partition 18 to provide an annular drainage space 19 connected to a

2

drain pipe 20. The extension has hand hole openings 17' therein.

A bag 21 of rubber composition or other suitable flexible material fits within the container and has a folded or molded edge portion 22 forming an annular channel or pocket 23 receiving the upper end of the container 6 and abutting at its bottom 24 against the top of the flange 7, the upper end of said channel forming a rounded top edge 25 for the bag. In this form of the invention a tubular metal casing extension 26 provided with drainage openings 27 and flanged base ring portion 28 has the bottom surface 29 thereof reversely curved to fit over the top edge 25 of the bag and provide a curved inner abutting surface 30 for the bag when it is flexed upwardly during the operation of the extractor. To clamp the edge portion of the bag to the container and to hold the ring portion of said extension in assembled relation with the container 6, a sectional clamping ring formed of two or more segmental ring sections 31 with a channel faced inner side 32 is used. The top flange 33 of the clamping ring abuts the top surface of the outwardly extending flange of the base 28 and the bottom flange abuts and has an inclined face 34 abutting a similar face on the bottom side of the flange 7 to form a wedging connection therewith which draws the ring portion 28 down into assembled relation with the top edge 25 of the bag when the ring sections 31 are secured together by the clamping bolts 35 which extend through the spaced ears 36 of said sections, these bolts also drawing the ring section firmly about the edge portion 22 of the bag to form a water-tight connection between the bag and the container.

A cover 37 has a slidably interlockable connection with the top ring portion 38 of the extension 17 and includes a rim portion 39, to which the top proper 40 is secured and a foraminous lining 41 spaced from but secured to a top plate 42 by a series of spacers 43, said lining fitting over the top of the extension 26. The space between the plate 42 and the lining communicates with the drainage space 19. The top of the casing extension does not take the weight of the cover, and when the fluid pressure is on, the cover may be slightly spaced therefrom. An inwardly extending locking flange 44 is secured to one-half of the top ring portion 38, and another inwardly flanged semi-cylindrical locking ring 45 is secured to one-half of the rim portion 39 of the cover. The flange 44 of the ring 38 is adapted to project over the upper part of one-half of the cover rim 39 when the cover is closed to hold this rim between it and the top ring 38 and thus prevent upward movement of the right hand half of the cover. The flange 46 of the ring 45 is adapted to project under one-half of the top ring 38 when the cover is closed while

one-half of the cover rim 39 projects over this same half of the top ring 38 to lock the left-hand half of the cover against upward movement relative to the casing. Because of the half locks thus provided, the cover may be moved laterally toward the side having the flange 46 to the open dotted line position shown in Fig. 1. For supporting the cover during opening and in its open position, a pair of suitably supported and spaced fixed rails 41 are provided upon which wheels 48 journaled in brackets 49 carried by the cover are mounted, so that the cover rides on the rails into and out of operative position with the casing.

The operation of the extractor is generally similar to that of the aforementioned application, the only difference being in the type of connection between the bag and the casing, the connection herein shown being of improved form and adapted to prolong the life of the bag and providing for a gradual flexing of the bag over the rounded surface 30 when the bag under the action of fluid under pressure introduced into the bottom of the container 6 is forced with the material to be treated between it and the cover upwardly to squeeze or compress said material between said bag, casing and cover so as to force the liquid content of said material out through apertures in the extension and cover.

In Figs. 4 and 5 I have shown an extractor in which the extension 26 is omitted and a short top ring 50 is substituted therefor. This ring 50 has an inwardly extending annular groove 51 formed therein providing a flanged base portion 52 having a curved bottom surface 53 similar to the surface 29 and providing a curved inner edge 54 abutting the bag when it is flexed upwardly during the operation of the extractor.

The sectional clamping ring is identical with the first described construction and has been similarly numeralled and acts to hold the bag to the casing and in assembled relation with the ring 50.

A cover 55 has an apertured lining 56 secured thereto in spaced relation and extends over the top of the ring 50, said cover having a bracket 57 secured thereto and carrying a pulley 58 for a hoist suspension rope 59 that may be used in connection with a swinging derrick shown in my prior U. S. Patent No. 2,336,428, dated December 7, 1943.

For holding the cover 55 in operative position and for transmitting the compression thrust from the cover to the frame 16, said frame has an angled extension 60 provided with inwardly extending angularly spaced locking lugs 61 adapted to be wedgingly engaged by lugs 62 on a locking ring 63 rotatably mounted on the cover and having an inwardly extending flange 64 engageable therewith. The locking connection between the lugs 61 and 62 is not designed to provide any downward thrust between said cover and the ring 50 when the cover is closed, but only to hold the cover against upward movement imposed by the load forced upwardly thereagainst when fluid pressure is introduced into the lower portion of the container 6 and acts

upon the bag 21. The space 65 between the angled extension 60 and the casing 6 forms an annular drainage space in which water forced out through the lining 56 may drain and be carried off through the drain pipe 66. The extension 60 is bolted to a flange 66' on the container 6, so that it may be dropped down to provide access to the clamping rings 31.

It is to be understood that this invention is not to be limited to any particular form or arrangement of parts except in so far as such limitations are included in the claims.

What I claim as my invention is:

1. In a compression extractor, the combination of a casing having a rounded upper edge and a flange provided with a wedging surface below said edge, a flexible bag extending into said casing and having a rounded channeled upper edge fitting over the rounded edge of said casing with a portion extending downwardly over the outer side of said casing below its upper edge, a member having a flanged ring portion with a reversely curved surface engageable with the top of the rounded edge of the bag, a sectional clamping ring engageable with the downwardly extending portion of said bag and having inwardly extending flanges to engage the flanged ring portion of said member and to wedgingly engage said wedging surface of the flange on said casing, and means securing the sections of said ring together and in clamping engagement with the bag and in wedging engagement with said flange on said casing.

2. In a compression extractor, the combination of a casing having a rounded edge and a flanged portion below said edge, a flexible bag extending into said casing and having a rounded channeled upper edge fitting over the rounded edge of the casing with a portion extending downwardly over the outer surface of said casing, a member having a ring portion provided with a flange and with a curved surface engageable with the top of the edge of the bag, and a separable clamping ring engageable with the flanges of said casing and said member and with the downwardly extending portion of the bag for clamping said portion in fluid-tight engagement with and against the outer surface of said casing and clamping said ring in assembled relation with said casing.
